DISPLAY HOLDER

Robert T. Sutton, Springfield, Ill.

Application December 2, 1958, Serial No. 53,624

Term of patent 14 years

(Cl. D80—9)

Figure 1 is a perspective view of a display holder showing my new design, looking downwardly from a position opposite a front corner thereof, and illustrating the elements of the holder in their normal operating alignment;

Figure 2 is a side elevational view of the holder shown in Figure 1;

Figure 3 is a top plan view of the same;

Figure 4 is an end elevational view of the same looking from the right-hand end thereof, as oriented in Figure 1; and

Figure 5 is a cross-sectional view taken substantially

at line 5—5 of Figure 3 and looking in the direction of the arrows thereon.

I claim:

The ornamental design for a display holder, substantially as shown.
